GAME BOARD

Norman T. White, Baltimore, Md.

Application May 19, 1954, Serial No. 30,556

Term of patent 7 years

(Cl. D34—5)

To all whom it may concern:

Be it known that I, Norman T. White, a citizen of the United States of America, residing at Baltimore, an independent city, and State of Maryland, have invented a new, original, and ornamental Design for a Game Board, of which the following is a specification, reference being had to the accompanying drawings, forming a part hereof.

Fig. 1 is a plan view of one side of the game board showing my new design,

Fig. 2 is an edge view of the game board,

Fig. 3 is a plan view of the opposite side of the game board, and

Fig. 4 is an edge view of the game board with parts broken away to better show the game-piece confining rim of the board.

I claim:

The ornamental design for a game board, as shown.
